GRINDING WHEEL DRESSING APPARATUS

Helge Gösta Norlander, Stockholm, Sweden

Application September 18, 1951, Serial No. 247,159
In Sweden October 4, 1950

2 Claims. (Cl. 125—11)

1

The present invention relates to an apparatus for dressing grinding wheels and more particularly to an apparatus for dressing a grinding wheel while the latter is being used.

One of the objects of the present invention is to provide an apparatus for dressing a grinding wheel while the latter is being used so that objects may be ground under mass production methods while maintaining the trueness of the grinding wheel.

A further object of the present invention is to provide an apparatus of the above type which derives its movement solely from the translational movement of the grinding wheel support.

Another object of the present invention is to provide an apparatus of the above type which is fully automatic.

A still further object of the present invention is to provide an apparatus of the above type which does not require any gearing or other power transmission means to automatically dress the grinding wheel.

Yet another object of the present invention is to provide an apparatus of the above type which only removes material from the grinding wheel in order to dress the same simultaneously with the use of the grinding wheel and by amounts corresponding to the wear of the grinding wheel during the use thereof.

The novel features which are considered as characteristic for the invention are set forth in particular in the appended claims. The invention itself, however, both as to its construction and its method of operation, together with additional objects and advantages thereof, will be best understood from the following description of the specific embodiment when read in connection with the accompanying drawing.

Referring now to the drawing, it will be seen that the apparatus of the present invention comprises a base member 1 upon which a support member 2 is mounted and guided for slidable movement in the direction of the arrow shown at the upper part of the drawing. The grinding wheel 3 is mounted on the support member 2 for rotation with respect thereto and is adapted to be moved in translation with support member 2 in the direction of the arrow shown at the top part of the drawing. Located on the base member 1 is a rotatably mounted work holding means 14, which is diagrammatically illustrated in the drawing and which may be any suitable chuck, for example. The work piece 13 is supported in the work holding means 14 so as to be ground by the grinding wheel 3, and it is evident that,

2

as the diameter of the grinding wheel decreases, the support member will be moved in the direction of the arrow shown on the top part of the drawing so as to maintain the grinding wheel in contact with the work piece 3. During such translational movement of the grinding wheel, the latter moves in a plane perpendicular to its axis and along a straight line extended toward the work holding means 14. As is apparent from the drawing, the support member 2 is provided with an extension 11 projecting therefrom and formed with a slot 10 which extends in a direction perpendicular to the direction of movement of the support member 2. The projection 11 may be formed integrally with the support member 2, as shown in the drawing, or may be a separate member fixedly connected thereto.

A mounting means 4 for mounting dressing tool means 5 is located adjacent to the grinding wheel 3. The dressing tool means 5 is adjustably located in the mounting means 4 by any suitable device, such as, for example, the screw member 12 which engages the mounting means 4 and the dressing tool means 5 for adjustably locating the latter in the mounting means 4. The mounting means 4 is provided with a sleeve portion 6 having a bore extending therethrough.

Fixedly mounted on the base member 1 is the shaft 7 which extends through the bore of the sleeve portion 6, and a key member mounted on the shaft 7 may be seen in the drawing, this key member engaging a keyway formed in the bore of sleeve 6 so that the mounting means 4 is mounted only for sliding movement along the shaft 7 in the direction of the arrow shown on sleeve portion 6 and cannot rotate about the shaft 7. The axis of shaft 7 is located in the above-mentioned plane perpendicular to the axis of the grinding wheel 3 and makes a 45° angle with the straight line along which the grinding wheel 3 moves in translation in said plane when the support member 2 is linearly moved during the wearing away of the grinding wheel 3.

The extension 9 fixed to the mounting means 4 projects therefrom and has rotatably mounted thereon the roller 8 which engages the slot 10 of projection 11. As a result of this interconnection between the support member 2 and the mounting means 4, the movement of the support member is transmitted to the mounting means to move the same along the shaft 7, and the dressing tool means 5 is thereby constrained to move along a line at 45° to the straight line along which the grinding wheel moves in translation and at a rate of speed which is $\sqrt{2}$ times as great as the

rate of movement of the grinding wheel 3 and the supporting member 2 toward the work holding means 14.

As a result of the above construction, the dressing tool means 5 is maintained in contact with the periphery of the grinding wheel 3 while the latter operates upon a work piece 13, for example, so that during the time that the grinding wheel decreases in diameter from the size shown in solid lines in the drawing to the size showing dotted lines, the dressing tool means 5 moves from the position I to position II. Thus, the 45° angle of the dresser mount keeps the dressing tool means 5 in the horizontal diametrical line of the grinding wheel and moves the tool means 5 an amount radially of the wheel corresponding to the reduction of wheel diameter due to wear which is substantially the amount the wheel is lowered to maintain contact between the wheel and the work.

The above described apparatus is particularly suitable where extremely accurate grinding is required in the mass production of various articles. For example, the above apparatus is particularly suitable for the grinding of rollers, drills, and in connection with the grinding of twist drills, the above apparatus is particularly suitable for the grinding of spiral grooves in these drills. In the grinding of exceedingly small twist drills, even the slightest variation in the spiral grooves produces an exceedingly inferior drill because such variation will tend to cause the drill to drill along a line inclined to its axis. The above apparatus, however, guarantees the proper grinding of accurate spiral grooves under mass production methods.

The dressing tool means 5 is more or less schematically illustrated in the drawing, and it is evident that the invention may be used with any type of dressing tool.

It will be understood that each of the elements described above, or two or more together, may also find a useful application in other types of grinding wheel dressing apparatus differing from the types described above.

While the invention has been illustrated and described as embodied in an apparatus for dressing a grinding wheel while the latter is being used, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A grinding apparatus, comprising in combination, support means mounted for linear movement; a grinding wheel rotatably mounted on said support means for rotation with respect thereto and for linear movement therewith so that said grinding wheel moves along a first

straight line located in a predetermined plane perpendicular to the axis of said grinding wheel; a mounting member located adjacent to said grinding wheel; fixedly mounted guide means operatively connected to said mounting member for moving the same toward said first straight line along a second straight line located in said plane and making a 45° angle with said straight line; dressing tool means fixedly mounted on said mounting member and located in engagement with the periphery of said grinding wheel; and connecting means interconnecting said mounting member with said support means for moving said mounting member along said second line only upon movement of said support member, said connecting means comprising a guide portion extending from said support means for movement therewith and being formed with a slot extending in a direction perpendicular to the linear movement of said support means and a roller member mounted on said mounting member and engaging said slot.

2. A grinding apparatus, comprising in combination, work holding means; support means mounted for linear movement toward said work holding means; a grinding wheel rotatably mounted on said support means for rotation with respect thereto and for linear movement therewith so that said grinding wheel moves along a first straight line located in a predetermined plane perpendicular to the axis of said grinding wheel and extending toward said work holding means; a mounting member located adjacent to said grinding wheel and being formed with a bore extending therethrough; a fixedly mounted shaft member located adjacent to said grinding wheel and having the axis thereof located in said plane and making a 45° angle with said straight line, said shaft member extending through said bore of said mounting member to support the latter for slidable movement along said shaft member; dressing tool means fixedly mounted on said mounting member and located in engagement with the periphery of said grinding wheel; and connecting means interconnecting said mounting member with said support means for moving said mounting member along said shaft only upon movement of said support member, said connecting means comprising a guide portion extending from said support means for movement therewith and being formed with a slot extending in a direction perpendicular to the linear movement of said support means and a roller member mounted on said mounting member and engaging said slot, whereby said dressing tool means is maintained in contact with the periphery of said grinding wheel as the diameter of the latter decreases during use on a work piece mounted on said work holding means.
